UNITED STATES PATENT OFFICE

FRANCESCO NOVELLI, OF PESCARA, ITALY

METHOD OF AND APPARATUS FOR BURNING SOLID FUEL

Application filed May 21, 1927, Serial No. 193,153, and in Italy May 27, 1926.

The present invention concerns a novel combustion process applicable to all the heating, cooking and melting furnaces, as for instance furnaces for steam boilers, for bricks, earthenwares, lime, and glass ovens and the like wherein is burnt pitcoal, lignite or similar combustibles adapted to be gasified.

According to my improved process, in order to obtain best thermal efficiency from the fuel burnt, all the gaseous constituents are first burnt and then the solid residue either wholly or in part.

With the said object in view I introduce into the combustion chamber of the furnace 15 retorts filled with the combustible, which retorts may be placed vertically, horizontally or in an inclined position according to the particular requirements; said retorts are provided with holes in their walls through which 20 the gaseous distillation products of the combustible can escape.

The operation is started by a preliminary heating effected with any convenient fuel outside of the retorts and in such quantity as 25 will suffice for initiating the distillation of the combustible contained in the retorts.

When the distillation has begun, the gases 30 which escape from the holes in the walls of the retorts take fire and burn in the furnace thereby furnishing the heat required for the action of the furnace and also insuring the distillation, so that no other extraneous fuel is required for obtaining the reduction coke of the combustible contained in the retorts.

35 At this point the combustion can be stopped, when the coke obtained may be otherwise utilized, or even sold with profit, and in that case, the number and the size of the retorts must be so selected that the operation 40 to be performed by the oven be completed at the end of the distillation. If, on the contrary, the work of the oven is continuous, means must be provided for the change or re-loading of the retorts at the end of the distil- 45 lation.

When the coke thus obtained cannot be otherwise employed it may be, wholly or at least partly, burnt in the same retorts wherein the distillation has been effected.

50 For this purpose the number, the arrange-

ment and the size of the holes provided in the walls of the retorts as well as the volume of the air admitted and the time of this admission are regulated in such a manner that, when the generation of the gases has stopped, 55 the combustion of the coke within the retorts is established by means of the air current which enters through said holes into the retorts.

By leaving at the end of the operation a 60 certain quantity of coke unburnt, one can utilize this residual quantity in a subsequent operation for starting the combustion in the manner above explained.

By way of example I have shown on the 65 annexed drawing a brick furnace of the Hofmann type adapted to operate in accordance with the present invention, and in said drawing:

Figures 1 and 2 show a vertical cross section of the furnace and, partly, a longitudinal section thereof Fig. 1 being a section along line I—I in Fig. 2, and Fig. 2 a section along line II—II in Fig. 1, while 70

Figure 3 shows a structural detail. 75

In the well known type of brick furnaces the fuel is introduced into the combustion chamber by letting it drop through charging holes 12 provided in the roof of the furnace.

In the furnace according to this invention I provide, under the said charging holes, 80 cylindrical retorts 2 comprising a suitable number of sections of refractory material. At their upper end said retorts are each provided with a removable cover 3 and in their peripheric walls with a number of holes 4. Through their lower open end they communicate with a horizontal flue 5 extending under the bottom of the chamber 1 in a direction contrary to the progress of the fire and opening at 10 a certain distance from the bottom of the chamber 1. The retorts containing pit coal, lignite or similar combustibles need not be placed under all the charging holes 12. 90

After the retorts have been completely, or partly, filled with combustible (according as it is desired to bake in a single operation a larger or a lesser quantity of bricks, it being besides very easy to introduce more coal into the retorts even when the combustion is 95 100

fully running) and the retorts become incandescent, the coal contained therein begins to distill, the combustion gases escape through the holes 4 and the lower outlets and immediately ignite.

5 Tests, many times repeated, have shown that, without a change in the size and the other arrangements of the usual furnaces the heating can be effected only by means of the gaseous portion of the fuel, leaving in the retorts a quantity of coke which amounts to about 80% in weight of the coal shared into the retorts.

10 The coke thus obtained can be utilized for any desired purpose. When there are no facilities for utilizing it for other purposes and it is not convenient to sell it, the quantity of coal introduced into the retorts, the number, the arrangement and the size of the holes 15 provided in the walls of the retorts for the escape of the gases, and the quantity of the air admitted to the furnace are regulated in such manner that at the end of the distillation the coke produced begins to burn in its turn, 20 its combustion being sustained by the air which reaches the interior of the retorts through the holes in their walls.

25 Thus is utilized on the spot not only the entire heat of combustion of the gaseous portion of the fuel, which up to day has been mainly lost, but also, and completely, the heat of combustion of the solid portion, and this complete utilization of the fuel is obtained in the best and most convenient manner, in that 30 either the coke is burnt within the retorts wherein it has been produced, or it is burnt in the furnace between the retorts. The furnace is completed by the channel 7 which serves for the exhaust of the smoke through 35 the funnel 8 and the manholes 9 of the furnace.

40 However in any case, in order to obtain the result desired, the quantity of the air to be supplied, by any convenient means most suitable for the particular kind of furnace, must be nicely adjusted for sustaining the combustion in the manner prescribed without being in excess or deficient.

45 It will be apparent that this improved method of combustion is suitable not only for brick, earthenware and lime furnaces but also for all those furnaces in the combustion chambers, of which, (or in adjoining auxiliary chambers) it is possible to place distillation retorts, and it is also apparent that in 50 said furnaces either between the retorts or upon specially prepared grates it is possible to effect together with the combustion of the gases escaping from the retorts, the combustion of the coke obtained in same.

55 I claim:

60 A furnace comprising a combustion chamber having in its top a plurality of charging holes having removable covers, vertical, tubular retorts disposed beneath and in corre-

spondence with certain of said charging holes whereby fuel may be introduced through the remaining charging holes for heating said retorts, said retorts having perforations in their walls, a gas passage provided at the lower end 70 of each of said retorts, said passages extending downwardly beneath the bottom of said combustion chamber and then upwardly to open into the combustion chamber at the bottom thereof.

75 In testimony whereof I have affixed my signature this fifth day of May, 1927, at Rome in the Kingdom of Italy.

FRANCESCO NOVELLI.
